UNITED STATES PATENT OFFICE

2,441,736

DRIER FOR PNEUMATIC FEED COAL
STOKERS

Ernest C. Webb, Cleveland, Ohio, assignor to Iron
Fireman Manufacturing Company, Portland,
Oreg.

Substituted for abandoned application Serial No.
487,505, May 18, 1943. This application October
7, 1946, Serial No. 707,549

1 Claim. (Cl. 34—182)

1

This patent is a substitute for applicant's abandoned application, filed May 18, 1943, Serial No. 487,505.

This invention relates generally to the burning of coal, and particularly to a coal drier.

The main object of this invention is to prepare coal for burning with a spreader stoker by drying it sufficiently to prevent accumulation, packing or caking of material in the bends and pipes of the coal feeding mechanism, regardless of the moisture content or percentage of dirt and clay contained within the coal as it enters the stoker.

The second object is to construct a drier for spreader stokers wherein the progress of the coal from the point of storage to the point of delivery will be retarded and the coal at the same time agitated and aerated by a stream of warm air for the purpose of removing the moisture therefrom, and for the purpose of preventing the formation of cakes or lumps, or breaking up lumps of frangible materials existing in the incoming fuel.

The third object is to construct a drier for the purpose above stated especially adapted to be inserted in a coal delivery line of a spreader stoker in which conveying and combustion air cannot find their way to the drier, and in which the drying air is made to travel a tortuous path through the drying compartment in order to increase the length of the drying time.

The fourth object is to construct a drier of the class described in which the amount of fuel carried off by the drying air will be reduced to a minimum, and in which the moisture extracted from the fuel is delivered to the combustion compartment of the furnace.

I accomplish these and other objects in the manner set forth in the following specification, as illustrated in the accompanying drawings, in which:

Fig. 1 is a fragmentary side elevation of the apparatus showing a portion of the front of a furnace in section.

Fig. 2 is an enlarged longitudinal section through the coal feeding worm and drier unit, taken along the line 2—2 in Fig. 3.

Fig. 3 is a horizontal section taken along the line 3—3 in Fig. 2.

Fig. 4 is a broken vertical section taken along the line 4—4 in Fig. 2.

Similar numerals refer to similar parts throughout the several views.

Referring in detail to the drawing, there is shown a furnace 10 whose front 11 has an open-

2

ing 12 communicating with the combustion chamber 13.

Projecting through the door 11 is a nozzle 14 whose tip 15 is hinged to the nozzle 14 by means of the pin 16, and the angularity of the tip 15 is controlled by means of a threaded hand wheel 17 on the bolt 18 which passes through the bracket 19 on the nozzle 14 and is connected to the tip 15 by means of the pin 20.

10 Powdered and crushed coal 21 is delivered to the nozzle 14 by means of the pneumatic conveyor pipe 22 which, for the purpose of providing overhead clearance in front of the furnace, is bent upwardly as shown in Fig. 1; and it is for the 15 purpose of preventing the building up of materials at the bends 23, 24 and 25 of the pipe 22 that my drier unit has been devised.

At the bottom end 26 of the pipe 22 is connected the upright tubular riser 27 whose lower 20 end 28 rests upon the floor 29, and whose opening 30 is connected with the discharge pipe 31 of the conveying air fan 32.

25 Communicating with the riser 27 is a coal tube 33 which connects by means of its flanged end 34 with the end 35 of the drier unit whose end 36 is connected by means of the coal tube 37 with the hopper or coal bin 38.

Extending axially through the tubes 33 and 37 is a coal worm shaft 39 provided with means 30 for rotating same (not shown). The shaft 39 has mounted thereon a helical flight 40 which extends from the coal bin 38, through the tube 37 into the drier unit where it joins with a slightly larger flight 40—A which extends across the 35 major portion of the drier unit and then connects with the smaller flight 40—B which is preferably the same diameter as the flight 40. The flight 40—B extends to the riser 27.

Although the flight 40 occupies the larger portion 40 of the tube 37, the flight 40—A is spaced from the rounded bottom 41 of the drier unit whose side walls 42 are tangential to the bottom 41, and whose vertical portion 43 form a rectangular box over which is placed a cover 44 provided with the inlet opening 45 through which air can be drawn through the pipe 46 which is connected with a source of heat, preferably the combustion space 13 of the furnace itself.

The cover 44 is also provided with an outlet 50 opening 47 which is connected by the pipe 48 to the inlet 49 of the conveying air fan 32. Clean-out openings 50 are provided in one of the walls 43 and are normally closed by the covers 51.

Below the cover 44 is placed the diagonal, vertical baffle plate 52 which is held in place by the

rivets 53. Attached to the baffle 52 is a sloping baffle 52-A whose downward vertical side 52-B is parallel with the longer sides 43 of the drying unit.

The section of the conveying flight 40-A between the ends 34 and 36 is provided with the paddles 54 which are set at a greater pitch with relation to the axis of the shaft 39 than are the flights of the conveyor 40-A themselves. The purpose of the paddles 54 is to stir or shovel the coal 21, exposing all of the material to the drying action of the air coming in from the pipe 46. If clay, or other material is present which would cake in the presence of heat, it is broken up while soft and friable, and not permitted to bake in enlarged form either before or after it enters the pipe 22.

The flight 40-B terminates at the riser 27 and the shaft 39 has secured on the end which projects into the riser 27, a blade or vane 56, the purpose of which is to loosen or separate the coal 21 as it enters the air stream from the fan 32.

On the shaft 39 is also secured a smaller but wider plugging or sealing flight 57, the purpose of which is to cause the tube 33 to fill with fuel and prevent air from the fan 32 blowing through the drying unit or into the hopper 38.

A crushing flight 58 is placed on that portion of the shaft 39 which is within the coal tube 37, its purpose being mainly to prevent larger pieces of coal 59 from entering the drier unit or the coal tube 33. The flight 58 also serves to keep the tube 37 full of coal and discourage any tendency of air to flow through the tube 37 in either direction, although the natural tendency is for air to flow from the hopper 38 to the drying unit under the influence of the fan 32.

The operation of the device is as follows:

Assuming that the shaft 39 is being rotated in a manner to move coal from the hopper 38 to the furnace 10, and that heated air is circulating through the drier unit, it can be seen that as the coal passes from the tube 37 through the end 36 into the drier unit, some of the coal falls outside of the reach of the flight 40-A, but into the path of the paddles 54, causing the coal to be carried around in a circumferential direction while the speed of its longitudinal direction of travel is decreased owing to the greater cross sectional area of the drier unit bottom 41.

As the coal enters the tube 33, it tends to fill this tube up and to be discharged into the air stream of the conveying air fan 32. By this time, the coal and dirt and clay have been robbed of so much of their moisture that they will not build up or collect at the bends 23, 24 and 25, but will pass on out of the tip 15 into the combustion chamber 13, as it is desired that they should in order to satisfactorily stoke the furnace.

I claim:

A coal drier for pneumatic spreader coal stokers comprising a worm conveyor for delivering coal from a storage space, a pneumatic conveyor to which coal is fed by said worm conveyor, the end-5 most portions of the worm conveyor having close fitting conveying tubes, the intermediate portion of said worm conveyor being enlarged to provide a substantial amount of clearance space around the worm of said conveyor, the portion of the 10 worm having the enlarged clearance having paddles secured thereto operating in said clearance space, the bottom of said clearance space diverging outwardly to form a trough, said trough having vertical sides and ends above the sloping portion 15 thereof, and having a rectangular horizontal top, said top having air inlet and outlet openings at opposite ends thereof, a diagonal vertical baffle plate extending across said box between said inlet and outlet openings, a downwardly sloping baffle under the inlet opening having a down-turned lower edge near the vertical longitudinal plane passing through said conveyor, the portion of 20 the worm housing on each end of said trough 25 having sealing flights formed thereon adapted to cause the coal tube to fill at the inlet and outlet ends of the trough.
